Application October 23, 1946, Serial No. 705,102
In France November 12, 1945

8 Claims. (Cl. 103—120)

1

The present invention relates to a hydraulic apparatus which may operate as a pump or as a hydraulic motor, and more particularly to a hydraulic apparatus comprising a stator and a rotor defining an annular chamber into which at least one retractable movable blade, and at least one stationary partition projects.

It is the object of the present invention to provide a perfect axial balance of the rotor by means of the operating fluid of the apparatus.

It is another object of the present invention to provide means for controlling the axial position of the rotor of the apparatus.

It is a further object of the invention to provide a hydraulic apparatus wherein movable blades are urged by fluid pressure into an annular blade chamber.

It is a still further object of the invention to provide a valve member for adjusting the axial extension of the blade chamber so as to control the output of the apparatus.

With these objects in view the present invention mainly consists in a hydraulic apparatus comprising a cylinder member formed with two coaxially arranged cylindrical bores, namely, a wider cylindrical bore and a narrower cylindrical bore which are connected by a transversal annular surface portion. The wider cylindrical bore at one end of the cylinder member is closed by a transversal end wall, and a piston is arranged within the cylinder member axially slidably and turnably relative to the same. The piston is provided with a narrower cylindrical portion fitting into the narrow cylindrical bore of the cylinder member, and with a wider cylindrical portion fitting into the wider cylindrical bore of the cylinder member.

Consequently, between one of the transversal end faces of the piston member and the end wall of the cylinder member a chamber is formed which during operating contains a fluid cushion and serves as a balancing chamber.

The cylindrical portions of the piston member are connected by an annular transversely extending surface portion so that within the wider bore of the cylinder member an annular chamber is formed.

The piston member is provided in the cylindrical surface of its wider portion with at least one axially extending recess communicating at one end with the annular chamber and at the other end with the balancing chamber.

At least one blade member is arranged in the recess in the piston member movably in axial direction of the same so as to project into the an-

2

nular chamber, so that the same constitutes a blade chamber.

A partition is mounted on the cylinder member projecting into the annular blade chamber and divides the same, together with the blade, into a delivery portion and a suction portion.

A valve member is mounted on the cylinder member slidably in axial direction thereof and engages the surface of the piston member in the 10 region of a transversal circular groove extending around the piston member. The valve member is provided with two ports arranged on either side of the circular groove, one of the ports communicating through conduits with a delivery portion of the annular blade chamber and the other port communicating through the conduits with the suction portion of the annular blade chamber. The groove communicates through a further conduit with the balancing chamber, and means are provided for adjusting the position of the valve member in relation to the groove.

The invention will be best understood from the following description of specific embodiments when read in connection with the accompanying drawings, in which:

Fig. 1 is a cross-sectional view taken on line 1—1 of Figure 2;

Fig. 2 is a partial longitudinal sectional view through the embodiment shown in Fig. 1;

Fig. 3 is a longitudinal sectional view of a preferred embodiment of the present invention taken on line 3—3 in Fig. 5;

Fig. 4 is a longitudinal sectional view taken on line 4—4 in Fig. 5;

Fig. 5 shows several partial cross-sectional views on lines 5—5 and 5'—5' in Fig. 3 and on line 5—5 of Fig. 4; and

Figs. 6 and 7 illustrate details.

In the example illustrated in Figs. 1 and 2, the apparatus includes a cylindrical member or stator 1 formed with an inner cylindrical chamber containing a coaxial cylindrical rotor 2. The transversal end faces of the rotor slidably engage the transversal end walls of the member 1 and, having a diameter smaller than that of said inner cylindrical chamber defines inside the latter an annular chamber 5. Bars or partitions 6, 7 are secured to the stator 1 at two diametrically opposed points thereof and their machined faces *a*, *b* engage the periphery of the rotor and fluidtightly subdivide the annular chamber 5 into two separate portions into each of which opens a port 9, and 10 respectively passing through the stator adjacent to the partitions 6, 7. Inside the rotor 2, are formed radial slots

11, the number of which is six, intersecting one another so as to form a chamber 12; at the centre of the chamber 12 inside the radial slots are housed blades 13 having peripheral faces constituted by a cylindrical surface having the same radius as the stator chamber; the thickness of each blade is constant but the width m , n of the inner end of this blade is higher than the width p , q of the outer end (Fig. 2). Each blade is provided with a lateral projection 14 on which is mounted a ball bearing 15 housed inside a groove 16 cut in one of the end walls of the stator.

The operation of the apparatus is as follows:

When the rotor 2 is caused to rotate, say in the direction of the arrow f after the ports 9 and 10 have been suitably connected to a fluid supply in the position illustrated in Fig. 1 the blades 13 assume the positions III and VI while registering with the partitions 6 and 7 completely retracted inside the rotor 2, and their rollers 15 roll over the sections g , h , and j , k of the cam groove 16. These sections are designed so as to allow only a progressive outward movement of the blades under the action of the pressure prevailing in the central chamber 12 communicating permanently through the channel 17 (Fig. 2) with the part of the apparatus where the fluid is under pressure. At the points h and k of the cam groove 16, the peripheral faces of the blades are in contact with the stator 1 so as to fluidtightly engage the latter without exerting any substantial pressure on it, while the thrust is absorbed by the walls of the cam groove 16. During the same time the blades extending in the position I and IV enter respectively the position II and V, while their rollers 15 travel through the section $h-i$ and $k-p$ of the cam groove; these sections are circular and coaxial with the stator and rotor whereby the blades have no radial displacement during this part of their rotation; during the same stage of operation, the blades originally in the positions II and V approach the positions III and VI in which they are completely retracted inside the rotor; their progressive inward motion is executed under the action of the sections $i-j$ and $l-g$ of the cam groove which are symmetrically arranged with reference to the section $h-g$ and $k-j$ and these sections are such that the retraction of the two opposite blades is executed at the same time and at the same instantaneous speed as the outward movement of the two blades leaving the positions VI and III. The volume of the chamber 12 remains thus unaltered and on the other hand, the outward movement of the blades produces no pulsation affecting the output of the pump.

Obviously, it appears from the preceding disclosure, that the blades exert their hydraulic action as they move from the positions I and IV towards the positions II and V, as it is then that they suck behind them the liquid admitted through the port 9 and deliver in front of them into the port 10 the liquid sucked by the two preceding blades. Under such conditions, the output of the apparatus is perfectly constant at every moment and so is the speed of flow provided care is taken to give the ports 9 and 10 the same cross-sectional area as the annular blade chamber 5.

Grooves 19 are provided in the stator 1 so as to short-circuit the spaces on either side of the blades in their positions II and V and to thus balance the pressure on the two sides of the blades at the moment at which the inward move-

ment of these blades is to begin. Similar grooves 20 are provided in the stator in accordance with the location of the blades in the positions I and IV so as to balance the pressures on either side of these blades almost up to the moment at which they enter said positions I and IV.

If it is desired to make the apparatus operate as a hydraulic engine fluid under pressure is admitted through port 10 so that the apparatus rotates in a direction opposite to that shown by the arrow f . Since the base $m-n$ of the blades is wider than their outer edge $p-q$ the blades move outwardly, although the specific pressure on the two opposite ends of the blades remains the same.

Instead of the ports 9 and 10, it is possible to arrange ports 21 and 22 communicating respectively with the grooves 19 and 20 so as to allow direct passage of the fluid inside the apparatus involving a change in direction and consequently a minimum reduction of the losses.

The number of blades may be different from six and their radial displacement may be produced solely by mechanical means instead of being produced mechanically and hydraulically as disclosed hereinabove. A slope on the stator may for instance engage directly the edge of the blades.

In the embodiment illustrated in Figs. 3 to 7, the apparatus differs from the preceding one through the fact that the annular chamber 25 between the stator 26 and the rotor 27 extends only over a fraction of the length of said stator and rotor. According to this embodiment a cylinder member constituting the stator 26 is formed with a wider cylindrical bore 26a and a narrower cylindrical bore 26b which are connected by a transversal annular surface portion 30'. The wider bore is closed by an end wall 26'. A piston member 27 constituting the rotor is arranged within the cylinder member 26 and has a wider portion 29 and a narrower portion 29' connected by a transversal annular surface portion 29''. The length of the rotor 27 is less than that of the stator and it is slidingly keyed to the shaft 31 engaging the inside of the stator. The blades 32 are located inside recesses 32' parallel with the axis of the rotor and arranged at the periphery thereof. Each blade is adapted to slide inside one associated recess in a direction parallel to said axis; said blades are in contacting engagement through their inner surface with the bell shaped cam 33, the outline of which is similar to that of the groove 16 in the form of execution of Fig. 1. This cam is secured to two partitions 34 diametrically opposed to one another and similar to the partitions 6 and 7 of the preceding form of execution but capable in the present case of sliding in a direction parallel with the axis inside the cylinder member 26 along which they are guided, without being allowed any rotation. Each of these partitions 34 is provided with a cylindrical recess 35 forming a cylinder inside which may move a piston 36 bearing against the cylinder member 26. The space between the bottom of the cylinder 35 and its piston 36 communicates through a channel 50 with a point of the chamber 25 for instance at which the fluid is under pressure (Fig. 5). Thus the two partitions are urged against the piston member 27 whatever may be the axial position of the latter by the thrust thus produced at the bottom of the cylinder 35. The chamber 37 between the transversal end face 27' of the wider cylindrical portion 29 of the piston member, and the end wall 26' of the

cylinder member 26 is connected by a conduit 38 with a circular groove 39 on the periphery of the narrower cylindrical portion 29' of the piston member 27. In the cylinder member 26 is provided a recess 40 in which is slidably housed a slide valve member 41, the tail-piece 42 of which projects out of the apparatus. Two ports 43 and 44 are provided in valve face 41' at a distance from one another which is slightly greater than the width of the groove 39 and they are connected respectively with the delivery portion and with the suction portion of the blade chamber 25 through conduits 45 and 46 in the stator. As in the preceding example, the suction port 47 and the delivery port 48 are arranged at points of the cylinder member 26 located respectively between the positions, VI and I on one hand and II and III on the other, of the blades.

The operation of the embodiment shown in Figures 3 to 5 is generally the same as the operation of the embodiment shown in Figures 1 to 3. The following operation, however, is specific for the embodiment shown in Figures 3 to 5:

The blades 32 are urged by the pressure in the balancing chamber 37 into the annular blade chamber 25, and into contact with the cam means 33. Cam means 33 urge the blades into the balancing chamber and out of the blade chamber when the blades pass over a partition 34.

The slide valve member 41 forms a control arrangement for the rotor 27, the axial position of which is depending on that of the slide valve. By bringing one of the ports 43-44 in register with the groove 39, the pressure is increased or reduced in the balancing chamber 37, as the case may be, which causes a corresponding axial displacement of the rotor 27. The rotor will then remain in a position of equilibrium for which the groove 39 is positioned between the openings 43 and 44. Any variation in pressure in the chamber 37 will then produce an axial displacement of the rotor 27 which brings the groove 39 into communication with one of the ports 43 or 44 and returns the pressure inside said chamber to its original value and consequently returns the rotor into its position of equilibrium. The axial position given to the rotor 27 defines the volume of the annular chamber 25 and consequently the output per revolution of the apparatus, said output being thus finally adjusted through the position given to the slide valve member 41. The liquid contained in the balancing chamber 37 forms a cushion absorbing the axial thrust exerted on the rotor by the liquid passing through the annular blade chamber 25.

Fig. 7 shows a modification of the slide valve 41 which includes, in this case, a plurality of ports 43' and 44' located at different distances from the position of equilibrium T of the groove 39, the cross-sectional areas of which increase with the distance. Thus if there is produced an important relative displacement between the slide valves and the rotor, the output of fluid through the conduit 38 may be sufficiently considerable for producing a rapid return movement of the rotor; moreover the stabilisation of the rotor is improved as the groove 39 registers automatically with one of the ports 43' or 44' the output of which corresponds to the leak output producing a modification in the pressure inside the chamber 37.

The slide valve 41 may be located at any desired point of the stator but preferably in a portion thereof corresponding to suction.

Of course my invention is by no means limited

to the details shown or described which have been given out solely by way of example. Thus for instance, Fig. 6 shows a modified control of the blades. According to said modification, the end portion 51 of each blade carries a projection 52 capped by a roller bearing rolling inside a cam groove 54 cut in the stator. Cam groove 54 acts in succession through each side for the outward and inward movement of the blades. With this arrangement, the stroke of the blade assumes a constant value whatever may be the output whereas with the above described system the stroke of the blades varies in the same way as the output, which is of great advantage.

The variable output apparatus do not include of necessity blades with a displacement parallel to the axis although this arrangement is preferable; they may be provided with radially moving blades; on the other hand, the apparatus with a constant output may include blades adapted to move in parallelism with the axis instead of being arranged radially as in the example described.

Instead of a rotor adapted to move axially as a unit as described hereinabove with reference to the form of execution of a variable output apparatus, it is possible to provide the rotor with an axially movable ring of which one side forms a movable wall defining the annular chamber transversely with reference to the axis. It is also possible to form this movable wall by the surface of a ring sliding axially with reference to the stator or else these different means may be associated for modifying the volume of the annular chamber.

The axial displacement of the partitions of the variable output apparatus may be ensured through a spring instead of hydraulically as in the example disclosed.

A further improvement for the apparatus described in the case where the blades are movable in parallelism with the axis of rotation, consists in giving the slots housing the blades a cross-sectional shape which is throttled down from the inner end to the outer end; the part of the blades which is located inside said slots has of course a corresponding shape and preferably in order to make the machining easier, said cross-section should assume the shape of a fraction of a circumference above one half circumference.

Many other modifications of the above described embodiments may be contemplated. For instance that part of each slideable transverse partition, such as 34 in Fig. 3, which is fitted in the stator may have such a cross-section that it is restrained by its housing against any radial motion; for this purpose said cross-section is preferably that of a circle portion greater than half a circle, but it might also be swallow-tailed or have any other similar throttled shape.

In the case where the blades are caused to project from their housings by a hydraulic thrust as described with reference to Figs. 3 and 4 it may be of advantage to assist this hydraulic control by a mechanical one, for instance a cam, similar but opposed to the cam 33 in Figs. 3 and 4, adjusted to operate with a small time lag with respect to the operation of the hydraulic control, so that the mechanical control will actually move the blades only when there is an abrupt loss of pressure.

What I claim is:

1. A rotary hydraulic apparatus comprising, in combination, a cylinder member formed with two coaxially arranged cylindrical bores, namely, a

wider cylindrical bore and a narrower cylindrical bore connected by a transversal annular surface portion, said cylinder member including an end wall closing said wider cylindrical bore at its end spaced from said narrower cylindrical bore; a piston member arranged within said cylinder member axially slidably and turnably relative to the same, and having two coaxially arranged cylindrical portions ending in transversal end faces, namely, a narrower cylindrical portion fitting into said narrower cylindrical bore and a wider cylindrical portion fitting into said wider cylindrical bore of said cylinder member, and arranged therein so as to form between one of said transversal end faces and said end wall of said cylinder member a balancing chamber, said cylindrical portions of said piston member being connected by a transversal annular surface portion, whereby within said wider cylindrical bore of said cylinder member a blade chamber is formed bounded on opposite sides by said annular transversal surface portions of said cylinder member and said piston member, said piston member being provided in its cylindrical surface with at least one axially extending recess, communicating at one end with said blade chamber and at its other end with said balancing chamber, said piston being also provided with a transversal circular groove in its cylindrical surface, and a conduit connecting said groove with said balancing chamber; means for rotating one of said members; at least one blade member arranged in said recess in said piston member movable in axial direction of the same so as to be adapted to project into said annular blade chamber; at least one partition means mounted on said cylinder member projecting into said annular blade chamber so as to divide—with the projecting portion of the blade member projecting through said blade chamber—said annular blade chamber into a delivery portion and a suction portion; a valve member mounted on said cylinder member slidable in axial direction thereof and having a valve face engaging the cylindrical surface of said piston member in the region of said transversal circular groove, said valve member being provided with two open-ended conduits each conduit having a port on said valve face, adapted to cooperate with said groove, one of said conduits being connected to the delivery portion of said annular blade chamber and the other being connected with the suction portion of said annular blade chamber, the ports of said conduits being spaced from each other a distance slightly larger than the width of said groove; and means for adjusting the position of said valve member in axial direction.

2. A rotary hydraulic apparatus comprising, in combination, a cylinder member formed with two coaxially arranged cylindrical bores, namely, a wider cylindrical bore and a narrower cylindrical bore connected by a transversal annular surface portion, said cylinder member including an end wall closing said wider cylindrical bore at its end spaced from said narrower cylindrical bore; a piston member arranged within said cylinder member axially slidably and turnably relative to the same, and having two coaxially arranged cylindrical portions, ending in transversal end faces, namely, a narrower cylindrical portion fitting into said narrower cylindrical bore and a wider cylindrical portion fitting into said wider cylindrical bore of said cylinder member, and arranged therein so as to form between one of said transversal end faces and said end

wall of said cylinder member a balancing chamber, said cylindrical portions of said piston member being connected by a transversal annular surface portion, whereby within said wider cylindrical bore of said cylinder member a blade chamber is formed bounded on opposite sides by said annular transversal surface portions of said cylinder member and said piston member, each of said annular surface portions being smaller than the surface of said end face of said piston member facing said balancing chamber, said piston member being provided in its cylindrical surface with at least one axially extending recess, communicating at one end with said blade chamber and at its other end with said balancing chamber, said piston being also provided with a transversal circular groove in its cylindrical surface, and a conduit connecting said groove with said balancing chamber; means for rotating one of said members; at least one blade member arranged in said recess in said piston member movable in axial direction of the same so as to be adapted to be urged by the pressure in said balancing chamber to move along said recess and to project into said annular blade chamber; at least one partition means mounted on said cylinder member projecting into said annular blade chamber so as to divide—with the projecting portion of the blade member projecting through said blade chamber—said annular blade chamber into a delivery portion and a suction portion; means urging said blade member during rotation to move in said recess out of said blade chamber whenever said blade member passes said partitioning means; a valve member mounted on said cylinder member slidable in axial direction thereof and having a valve face engaging the cylindrical surface of said piston member in the region of said transversal circular groove, said valve member being provided with two open-ended conduits each conduit having a port on said valve face, adapted to cooperate with said groove, one of said conduits being connected to the delivery portion of said annular blade chamber and the other being connected with the suction portion of said annular blade chamber, the ports of said conduits being spaced from each other a distance slightly larger than the width of said groove; and means for adjusting the position of said valve member in axial direction.

3. A rotary hydraulic apparatus according to claim 2, and including mechanical means for urging said blade member to move along said recess into a position projecting into said blade chamber, said mechanical control means being adjusted to operate with a small time lag with respect to the force exerted by the pressure in said balancing chamber so that said blade means are only moved by said mechanical means in case of a sudden drop of pressure in said balancing chamber.

4. A rotary hydraulic apparatus comprising in combination, a cylinder member formed with two coaxially arranged cylindrical bores, namely, a wider cylindrical bore and a narrower cylindrical bore connected by a transversal annular surface portion, said cylinder member including an end wall closing said wider cylindrical bore at its end spaced from said narrower cylindrical bore; a piston member arranged within said cylinder member axially slidably and turnably relative to the same, and having two coaxially arranged cylindrical portions ending in transversal end faces, namely, a narrower cylindrical bore and a wider cylindrical portion fitting into said wider cylindrical bore of said cylinder member, and arranged therein so as to form between one of said transversal end faces and said end

therein so as to form between one of said transversal end faces and said end wall of said cylinder member a balancing chamber, said cylindrical portions of said piston member being connected by a transversal annular surface portion, whereby within said wider cylindrical bore of said cylinder member a blade chamber is formed bounded on opposite sides by said annular transversal surface portions of said cylinder member and said piston member, each of said annular surface portions being smaller than the surface of said end face of said piston member facing said balancing chamber, said piston member being provided in its cylindrical surface with at least one recess extending in a diametral plane and communicating at one end with said blade chamber, means for rotating one of said members; at least one blade member arranged in said recess in said piston member movable in said recess so as to be adapted to project into said annular blade chamber; at least one partition means mounted on said cylinder member projecting into said annular blade chamber so as to divide—with the projecting portion of the blade member projecting through said blade chamber—said annular blade chamber into a delivery portion and a suction portion; means urging said blade member during rotation to move in said recess out of said blade chamber whenever said blade member passes said partitioning means; a fluid valve member mounted on said cylinder member and adapted to connect said balancing chamber either with the delivery portion of said blade chamber or with the suction portion of said chamber according as said piston member occupies the one or the other of two determined spaced axial positions in relation with the position of said valve member.

5. A rotary hydraulic apparatus as in claim 4, further comprising means for adjusting the position of said valve member thereby causing the volume of said annular chamber to vary.

6. A rotary hydraulic apparatus, comprising in combination, a cylinder member formed with two coaxially arranged cylindrical bores, namely, a wider cylindrical bore and a narrower cylindrical bore connected by a transversal annular surface portion, said cylinder member including an end wall closing said wider cylindrical bore at its end spaced from said narrower cylindrical bore; a piston member arranged within said cylinder member axially slidably and turnably relative to the same, and having two coaxially arranged cylindrical portions ending in transversal end faces, namely, a narrower cylindrical portion fitting into said narrower cylindrical bore and a wider cylindrical portion fitting into said wider cylindrical bore of said cylinder member, and arranged therein so as to form between one of said transversal end faces and said end wall of said cylinder member a balancing chamber, said cylindrical portions of said piston member being connected by a transversal annular surface portion, whereby within said wider cylindrical bore of said cylinder member a blade chamber is

formed bounded on opposite sides by said annular transversal surface portions of said cylinder member and said piston member, each of said annular surface portions being smaller than the surface of said end face of said piston member facing said balancing chamber, said piston member being provided in its cylindrical surface with at least one recess extending in a diametral plane and communicating at one end with said blade chamber and at its other end with said balancing chamber; means for rotating one of said members; at least one blade member arranged in said recess in said piston member movable in said recess so as to be adapted to be urged by the pressure in said balancing chamber to move along said recess and to project into said annular blade chamber; at least one partition means mounted on said cylinder member projecting into said annular blade chamber so as to divide—with the projecting portion of the blade member projecting through said blade chamber—said annular blade chamber into a delivery portion and a suction portion; means urging said blade member during rotation to move in said recess out of said blade chamber whenever said blade member passes said partitioning means; a valve member mounted on said cylinder member and adapted to connect said balancing chamber either with the delivery portion of said blade chamber or with the suction portion of said chamber according as said piston member occupies the one or the other of two determined spaced axial positions in relation with the position of said valve member.

7. A rotary hydraulic apparatus as in claim 6, further comprising means for adjusting the position of said valve member thereby causing the volume of said annular chamber to vary.

8. A rotary hydraulic apparatus according to claim 4, and including mechanical means for urging said blade member to move along said recess into a position projecting into said blade chamber, said mechanical control means being adjusted to operate with a small time lag with respect to the force exerted by the pressure in said balancing chamber so that said blade means are only moved by said mechanical means in case of a sudden drop of pressure in said balancing chamber.
